UNITED STATES PATENT OFFICE.

LEWIS O. CULVER, OF FORTYFORT, PENNSYLVANIA, ASSIGNOR OF ONE-THIRD TO
GEORGE W. CULVER, OF FORTYFORT, PENNSYLVANIA.

BOTTLE-STOPPER.

1,268,936.

Specification of Letters Patent. Patented June 11, 1918.

Application filed April 13, 1917. Serial No. 161,847.

To all whom it may concern:

Be it known that I, LEWIS O. CULVER, citizen of the United States, residing at Fortyfort, in the county of Luzerne and State of Pennsylvania, have invented certain new and useful Improvements in Bottle-Stoppers, of which the following is a specification.

My present invention relates to bottle stoppers and its principal object resides in the provision of a stopper which will insure a perfect air tight and leak proof joint, thereby retaining the contents of the bottle in perfect condition.

16 A second object of the invention is to provide a bottle stopper which may be quickly and readily engaged and disengaged from the mouth of the bottle and is constructed in such a manner as to obviate the necessity of employing bottle openers that are necessary in removing stoppers or closures of the conventional type from bottles.

Another important object is to provide a bottle stopper which includes a plurality of gripping members which are adapted to be engaged with the beading at the mouth of the bottle and thus positively retain the stopper or cork tightly engaged in the mouth of the bottle, and a novel operating means for disengaging these gripping arms from the beading on the mouth of the bottle. A further object of this invention resides in the provision of a closure having the above features and others which may be associated with any type of bottle now on the market and the parts of which being compactly associated and which are not likely to become broken.

Another general object is to provide a bottle stopper which is durable, efficient, consists of few parts, which may be manufactured and placed on the market at a minimum cost.

The invention embodies the combinations and arrangements and details of constructions which will be hereinafter specifically referred to and illustrated in the accompanying drawing in which,

Figure 1 is a view showing my improved stopper applied to a bottle; the bottle and part of my stopper being shown in section.

Fig. 2 is a top elevation thereof and,

Fig. 3 is a bottom elevation of the device detached from the bottle.

On the drawing in which like characters

of reference designate like parts the numeral 5 designates a neck of a bottle which is of the conventional type and has a beading 6 formed upon the periphery of the mouth thereof in the usual manner. This type of bottle is shown merely for the purpose of illustrating the invention and I wish to here state that my improved stopper is applicable to almost any type of bottle.

The numeral 7 designates a tubular casing 65 which may be formed of any desirable material and in any desired shape, in this instance this tubular casing is illustrated as being cylindrical. The casing includes a top wall 8 and a bottom wall 9. This bottom 70 wall 9 is provided with openings 10 which are arranged at diametrically opposite points. These openings 10 diverge from each other as is clearly illustrated in Fig. 1.

Secured to the under face of the bottom 75 wall 9 centrally thereof and between the openings 10 is a stopper or disk 11 which is preferably formed of rubber but however it may be formed of any other material possessing the necessary qualities. This 80 stopper 11 is secured in place by a fastening pin 12 which extends through the bottom wall 9 and through the center of the stopper 11. Washers 13 are secured to the opposite ends of this fastening pin 12 one of which 85 lies against the inner face of the wall 9 while the other bears against the under face of the disk or stopper 11. The washer upon that end of the pin which extends through the wall 9 is formed by flattening the same 90 while the washer at the opposite end is separable and it is held in place by forming the pin 12 with a head.

Reciprocable through the divergent openings 10 is a pair of resilient clamping or 95 gripping arms 14 which diverge from each other and are formed with hooks 15 at their extremities which are adapted to be engaged with the annular beading 6 on the bottle neck. These arms 14 are formed from a 100 single strip of resilient metal as is clearly illustrated on the drawing.

Reciprocable in the casing 7 and extending centrally through the top wall thereof is a stem 16 which is formed with a knob 17 105 at its outer end thereof. Connected to the apex of the meeting point of the spring arms 14 by soldering or otherwise is one end of a contractible coil spring 18, while the opposite end of this coil spring 18 is 110

secured to the stem 16. The function of this spring 18 is to normally urge the arms 14 outwardly and to retain the hooks 15 in gripping or clamping engagement with the beading 6.

Extending centrally through the casing 7 and horizontally thereof is a handle member 18 which is adapted to coöperate with the head 17 and rod 16 in disengaging the 10 clamping arms from the mouth of the bottle.

In order to engage the stopper 13 in the mouth of the bottle the palm of the operator's hand is engaged with the head 17 while the fingers are engaged with the 15 handle member 18. The stem 16 is now forced downwardly by exerting pressure on the head 17 which will compress the spring 18 and move the gripping arms 14 downwardly in the openings 10 which will cause 20 the hooks 15 to be moved away from each other. Upon releasing the head from the handle 17 and the knob 18 the gripping arms 14 will be moved upwardly and engage the hooks 15 with the beading 6 of the neck 5 25 and thus retain the stopper and cylinder 7 against any movement whatsoever.

This embodiment of the invention is now what is believed to be the preferred form but it is to be understood that the same is 30 susceptible to various modifications and alterations. It is to be further understood that the limits of modifications are only governed by the herewith appended claims.

What is claimed is:

35 1. A bottle closure including a stopper, a casing carried thereby and closed at each end, said casing having oppositely diverging openings in its lower end, a substantially V-shaped plate arranged within said casing and having its opposite ends extended 40 through said openings and bent to provide hooks, and a reciprocating rod secured to said plate at the apex thereof.

45 2. A closure, including a stopper, a casing carried thereby, said casing having op-

ositely diverging openings formed in its lower end, a rod movably supported by said casing, gripping members secured to said rod and movable through said openings to engage and release a bottle neck, said 50 gripping members being arranged to spread apart upon downward movement and to approach one another upon upward movement of said rod.

3. A closure, including a stopper, a casing 55 carried thereby said casing having oppositely diverging openings formed in its lower end, gripping members movable in said openings, an operating rod movably supported by said casing, and resilient 60 means connecting said rod and gripping members.

4. A bottle closure, including a stopper, a casing carried thereby, said casing having oppositely diverging openings formed in 65 its lower end, gripping members movable in said openings, an operating rod attached to said gripping members, and a gripping rod extending transversely through said casing.

5. A bottle closure including a casing 70 closed at each end, and having oppositely inclined openings formed in the lower end thereof, a stopper secured to the lower end of said casing between said openings, a gripping member movable within said casing 75 and comprising a strip bent intermediate its ends to provide diverging arms, said arms being movable outwardly through the inclined openings in the casing and having their extremities bent inwardly to provide 80 gripping hooks, a rod movable through the upper end of the casing, and a resilient connection between the lower end of said rod and said gripping member.

In testimony whereof I affix my signature 85 in presence of a witness.

LEWIS O. CULVER.
